United States Patent Office

Des. 193,676
Patented Sept. 25, 1962

193,676

BEVERAGE MIXER OR SIMILAR ARTICLE

Richard H. Taves, 10611 W. Nevada Ave.,
Melrose Park, Ill.

Filed July 24, 1961, Ser. No. 66,030

Term of patent 14 years

(Cl. D44—1)

Fig. 1.

Fig. 2.

FIGURE 1 is a perspective view of a beverage mixer or similar article showing my new design;

I claim:

The ornamental design for a beverage mixer or similar article, as shown.
